UNITED STATES PATENT OFFICE.

ARTHUR ROSENTHAL, OF GRAND RAPIDS, MICHIGAN, ASSIGNOR TO ROSE LABEL
MACHINE COMPANY, OF GRAND RAPIDS, MICHIGAN.

SEWING-MACHINE FOR ATTACHING LABELS.

1,142,057.

Specification of Letters Patent.

Patented June 8, 1915.

Application filed March 11, 1912. Serial No. 683,067.

To all whom it may concern:

Be it known that I, ARTHUR ROSENTHAL, a citizen of the United States, residing at the city of Grand Rapids, county of Kent, 5 and State of Michigan, have invented certain new and useful Improvements in Sewing-Machines for Attaching Labels, of which the following is a specification.

This invention relates to improvements 10 in sewing machines for attaching labels, and for similar uses such as attaching a reinforce piece or reinforcing by stitchings.

The objects of the invention are, first, to provide an improved presser foot structure, 15 including means for holding and supporting the presser foot and permitting the insertion of a presser foot of different dimension; second, to provide improved means of guiding such a presser foot, the guiding 20 means being adjustable to different sizes of presser feet to attach labels of different dimensions, or to do similar work.

Further objects, and objects relating to 25 details and economies of construction and operation will definitely appear from the detailed description to follow.

The objects of this invention are accomplished by the machine described in the following specification.

30 The invention is clearly defined and pointed out in the claims.

A machine constituting a preferred embodiment of this invention is fully illustrated in the accompanying drawing, forming 35 a part of this specification, in which:

Figure I is a perspective view of a sewing machine embodying the improved label attaching and sewing device. Fig. II is an enlarged detail plan view partly in section of the label holder and actuating means 40 taken on a line corresponding to the irregular line 2—2 of Fig. V, the sewing machine arm not being included. Fig. III is an enlarged detail perspective view of a portion 45 of the actuating means showing the adjustment of the toothed rack sections and other associated parts to different dimensions. Fig. IV is an inverted plan view of the label or work holder presser foot device and 50 supporting means. Fig. V is an enlarged detail sectional elevation taken on a line corresponding to line 5—5 of Fig. II, showing the relations of the various parts, the control lever means being shown in full

lines, and the sewing machine arm and actuating means being omitted. Fig. VI is an enlarged detail perspective view of the ratchet and pinion for actuating and feeding and controlling the movement of the label holder mechanism, the same being detached and inverted. Fig. VII is an enlarged detail perspective view of the detent pawl structure for the said ratchet wheel. Fig. VIII is an enlarged detail sectional view on a line corresponding to line 8—8 of Fig. V, showing details of the swivel pivot slide on which the label or work controlling mechanism oscillates. Fig. IX is an enlarged detail sectional plan view of the cam plate for controlling and guiding the feed device, the guide rollers and means being shown in position, the same being taken on a broken section line corresponding to line 9—9 of Fig. V. Fig. X is an inverted plan view of the guide means for engaging the cam plate, the position of the cam in relation thereto being indicated by dotted lines. Fig. XI is an enlarged detail transverse sectional view taken on line 11—11 of Fig. V, showing the elevating means for relieving the pressure and for elevating the label or work holder presser foot. Fig. XII is a detail perspective view of the under side of the sewing machine base plate, showing the lever for elevating and controlling the label or work holding presser foot.

In the drawings, similar numerals of reference refer to similar parts throughout the several views, and the sectional views are all taken looking in the direction of the little arrows at the ends of the section lines.

Considering the numbered parts of the drawing, the plate 1, arm 2, head 3, needle bar 4, and needle 5 are in the usual form for sewing machines, and the machine is driven in the way that is common and well known for power driven sewing machines. The details of these parts, therefore, are not gone into and are not illustrated, as they are of a usual well known form. This invention is associated with and is an addition to these parts, being principally secured to the plate 1, although it is connected to be operated and supported to some extent by other parts. The same appears here as an attachment, but it may be incorporated into the machine when the same is being manufactured.

A presser foot 6, suitably corrugated at 6^a on its under side coöperates with the needle, and the object of this invention is to properly guide this presser foot 6 after a label or work has been placed under it so that a row of stitches will be made entirely around the presser foot, attaching the label by completely stitching its edges.

The presser foot is engaged by a series 13 of pins 7, 8, 9 and 10, in suitable sockets 6' on its opposite sides and ends, the pins being spring pressed so that they can be depressed or withdrawn successively to permit the presser foot to pass the needle. The

15 said presser foot is supported entirely by the spring pressed pins referred to, which engage the sockets 6' on all sides for that purpose. The pins 7, 8 and 9 are all supported in precisely the same manner, and 23 are carried by suitable reciprocating heads 11 supported in slotted ways 12 in the carrier frame 14. These pins are urged into engagement with the presser foot by coiled springs disposed thereon. The heads 11 25 are adjustable on the pins by suitable set screws 11'-11', see particularly Fig. IV.

The pin 10 is secured adjustably on the yielding arm 15, which is pivoted at 16 on the frame 14, and is held yieldingly in position by the coiled compression spring 17 30 acting thereagainst. The pin 10 is screw threaded in its support, and when it is properly adjusted, it is retained in position by the lock nut 18. These various adjustments 35 of the pins permit the adjustment of the device for holding a presser foot of any required size within the dimensions of the machine, and enable the proper locating of the same. The frame 14 is carried 40 by the pivoted arm 19, being secured to the down-turned end thereof by suitable screws 19^a.

The arm 19 is secured to the actuating 45 lever frame 20 by hinged member 21 engaging a pivot pin 22, the said hinge member being secured to the frame 20 by screws 23, or other suitable means (see particularly Figs. III and V). This permits the frame 14 and the presser foot 6 carried thereby to 50 be elevated by swinging upon the said hinge. The arm 19 is held down by spring pressure by means of the coiled spring 24 on the vertical rod 25 secured to the needle end of the frame 20, the tension of the said spring 55 being adjustable by the thumb nut 26. These parts are carried by a base plate 27 which is secured to the sewing machine plate 1 by clamp screws 28 in the slots 29 thereof (see Figs. I and II), the same being 60 detailed particularly in Fig. II.

The actuating lever frame 20 is carried upon an adjustable fulcrum or swivel 30 which is clamped in a slot 31 of the base plate 27. A projection 32 engages in a top 65 groove 33 at each side of the slot and a

hexagon nut 34 engages a bottom groove 35 at each side, whereby this fulcrum or pivot can be very readily adjusted. A slide 36 is pivoted on this fulcrum and is retained in its place by the shouldered screw 70 37 above the same, so that the actuating lever frame 20 plays freely back and forth on this slide, which is located in the ways 38 formed thereon, so that the actuating lever frame 20 has a swivel action on the 75 pivot 30, and at the same time slides freely back and forth on slide 36, permitting its movement to be universal and under complete control.

The actuating lever frame 20 is driven by 80 the ratchet wheel 39 which is carried on a suitable hub projection from the axis of the pinion 39'. The pinion 39' is supported on the pointed bearings 40 and 42, the bearing 40 being screw threaded into the 85 base plate and locked in position by the lock nut 41, and the bearing 42 being supported by the supporting arm 43. It is screw threaded therein, and lock nut 44 is provided for locking the same in position. 90 A vertical cil hole 45 is through the entire bearing parts whereby the same can be effectively lubricated.

The ratchet wheel 39 is actuated by the pawl 47 carried on the pin 48 in yoke 46, 95 which is pivoted on the axis of the pinion 39'. A spring 49 holds the pawl in engagement with the ratchet wheel. The pin 48 terminates in a ball 50, which is one member of a ball and socket joint, by which the 100 link 52 is connected thereto. The rock shaft arm 51 is connected by the link 52 to the pin 48. The link 52 is connected by ball and socket joints 53-53 at each end to the parts named. The rock shaft arm 51 is 105 carried upon the feed rock shaft 54. Any rock shaft connected to the driving mechanism of the sewing machine will serve the same purpose. By this means it will be noted that whenever the feed shaft is rocked, 110 the ratchet wheel is advanced and the mechanism provided is operated. The right hand end of the actuating lever frame 20 comprises a rack structure which coöperates with a pinion by which this feed device is 115 operated for feeding the labels to the needle. A straight rack 58, with suitable teeth thereon, is disposed toward the back of the frame, and is held in place by screws 59. A straight rack 60 parallel therewith is at the front of the frame, and is retained in position by set screws 61 which support and control the position thereof. A curved rack 62 is toward the left or the needle end of this frame, and a corresponding curved rack 63 120 is on the opposite side thereof. These are clamped between the racks 58 and 60, the ends of these racks 62 and 63 being formed with gear teeth that exactly mesh with the gear teeth of said racks whereby they are 125 130

adjustable back and forth and are retained in correct operative relation. Because these are adjustable on the gear teeth, whenever they are adjusted the pinion which actuates 5 the same meshes with the gears without further fitting or adjusting. A cam structure is provided for guiding this actuating lever frame to maintain the pinion in mesh with the rack structure, so that the presser foot 6 10 will be correctly guided and the label fed in proper manner to the sewing machine needle to be stitched. A guide device for engagement with the cam is provided at the right hand end of the actuating lever 15 frame. This guide device comprises a disk 66 on the lower end of journal pin 67 which is retained in place by shouldered screw 68. A roller 64 to contact with the main cam 20 guide surface to follow the surface thereof is carried upon a journal pin 65 which projects downwardly from the disk 66. To insure proper engagement of the guide roller 64 at all times with the cam, a supplemental 25 guiding cam surface 72 is provided, over which a supplemental guiding roller 70 passes. This roller is borne on a pivot 71 on the disk 66.

The principal or lower cam surface 69 is disposed on the base plate 27 on the edge of 30 which the guide roller 64 travels, as will be seen from an inspection of Figs. IX and X. On top of this main cam 69 is the supplemental guiding cam surface 72, having projections 73 at each corner, which engage the 35 supplemental roller 70 and cause the disk 66 to turn on its pivot and guide the main roller until it correctly turns the corner. Owing to the fact that these rollers are both 40 carried upon the same pivot plate, the auxiliary roller 70 becomes disengaged from the said projection, owing to the pivoting thereof, and permits the travel around the same. The cam plates are made integral and are secured in place by the attaching screws 69.

45 The regular presser foot is omitted from this sewing machine, and to the presser bar 74 is secured a cam structure for withdrawing the presser foot supporting pins to permit the passing of the presser foot past the 50 needle of the sewing machine. This consists of a cam carrying plate or frame 75 containing radial slots 78 for the adjustment of the cam blocks 76, which are secured in the slots by set screws 77, as clearly appears 55 from an inspection of Figs. I and V. Secured to each reciprocating head 11, which carries the supporting pins 7, 8 and 9, are anti-friction rollers 79 carried on pins 80. When this actuating lever frame structure 60 20 is operated in stitching a label, these cams are acted upon successively by the rollers and force the pins 7, 8, 9 and 10 successively out of engagement, opening a space for the needle to pass, as each side is successively presented to be stitched, as clearly

appears in Figs. II and IV. A similar roller 79 on a pin 80 is on the end of the arm 15 for controlling its movement in precisely the same way. From this it will be seen that as the presser foot is moved into position for 70 the sewing of the label by the needle, the pins 7, 8, 9 and 10 are successively withdrawn from their depressions or sockets 6' on the presser foot, and the needle permitted to pass. This permits very rapid automatic 75 feeding of the label, as it can simply be placed under the presser foot and stitched by the outer edge being thus presented.

The elevating of the presser foot may be accomplished by any suitable means. Upwardly projecting sleeves 81 are screw threaded at 82 into the base plate 1 of the sewing machine. These are yoked together by the bar 83 which is clamped thereto by the tubular shouldered nuts 84. A yoke 85 85 is slotted at 86 at each end and is disposed between these parts and beneath the hinged bar 19. The slots 86 engage under suitable shouldered heads 88 on the upper ends of the elevating pins 87. The pins 87 are 90 acted upon by a pair of levers 89, fulcrumed at 90-90 on a suitable bracket 91 underneath the machine. (See Fig. XII.) A treadle or foot connection 92 extends to the floor beneath the machine whereby the operator can very readily raise the presser foot 6 for inserting a label.

From this somewhat extended description of the parts, the operation of the devices connected with this improved label 100 attaching machine will be readily understood. The operator, by depressing the foot control through connection 92, raises the presser foot 6. A label is inserted underneath the same, which can be conveniently 105 done owing to the open side of the presser foot holder. The label corresponds in size to the presser foot. The presser foot is then let down and the machine started, which very rapidly, step by step, automatically 110 feeds the entire periphery or edge of the label to the sewing machine needle. This is accomplished owing to the fact that the rock shaft 54 every time the needle reciprocates, advances the ratchet wheel 39 115 a step, which actuates the pinion 39' a corresponding amount, carrying the fulcrumed actuating lever frame around over the cam in conformity to the cam side, thereby inducing the correct movement of the presser 120 foot in its relation to the sewing machine needle. As the presser foot is passed around, owing to the cam devices for that purpose, the supporting pins therefor are successively depressed to permit the needle 125 to pass without obstruction.

It is very clear that the various parts can be quickly adjusted to accommodate labels of different sizes by substituting proper presser feet, thus making the machine serve 130

for a great variety of work. The invention can be adapted to any form of label.

The machine is adapted to add reinforcing patches at any desired point whether they are labels or not. Also, the machine will quickly and automatically insert stitching in any design, either as a reinforcement or as a mere ornament.

Having thus described the invention, what is claimed as new and desired to be secured by Letters Patent is:

1. In a label attaching machine, the combination with the bed, arm, head, needle bar and driving means of a sewing machine, of a supporting base plate secured to the bed of said machine; an actuating lever frame structure carried thereby comprising a gear toothed frame part with inwardly projecting gear teeth; a swivel slide on the said supporting plate engaging in suitable ways on the said actuating lever frame; a presser foot carrying arm hinged to the said actuating lever frame; a suitable spring for putting pressure thereon; a presser foot frame carried by said presser foot arm; a presser foot with socket depressions on the opposite sides and ends thereof; spring pressed pins engaging said depressions; cam devices to withdraw said pins successively as the presser foot is moved to feed the label to the needle; and means for actuating the said presser foot to coöperate with said cams, as specified.
2. In a label attaching machine, having a head, a presser foot with socket depressions on the opposite sides and ends thereof; a

presser foot frame to carry said foot; spring pressed pins engaging said depressions; suitable reciprocating heads for carrying said pins, radially disposed in said presser foot frame on three sides of said foot; a yielding arm with engaging pin for one side of said presser foot; a cam support carried by the head of said sewing machine, with suitable radial slots therein; cam members adjustable in said slots and disposed to coöperate with and actuate said pin members; friction rollers carried by the said reciprocating heads and yielding arm disposed to coat with the cam members whereby the pins are actuated and withdrawn successively; and means of actuating the said frame as specified.

3. In a label attaching machine, a presser foot with socket depressions on the opposite sides and ends thereof; spring pressed pins engaging said depressions; cam devices to withdraw said pins successively as the presser foot is moved to feed the label to the needle; and means for actuating the said presser foot to coöperate with said cams, as specified.

4. In a label attaching machine, the combination with a sewing machine, of a detachable presser foot; laterally yielding members for supporting the same; means for guiding said presser foot to the needle of the sewing machine; and actuating means for withdrawing said lateral supports successively to permit all sides of the foot to pass the needle, as specified.

In witness whereof, I have hereunto set my hand and seal in the presence of two witnesses.

ARTHUR ROSENTHAL. [L.S.]
